ATTORNEY.

UNITED STATES PATENT OFFICE.

SAMUEL POOLE, OF JACKSON, MICHIGAN.

DROP STEP.

Application filed May 22, 1924. Serial No. 715,024.

To all whom it may concern:

Be it known that I, SAMUEL POOLE, a citizen of the United States, residing at Jackson, in the county of Jackson and State of Michigan, have invented a new and useful Improvement in a Drop Step, of which the following is a specification.

My invention relates to a new and useful improvement in a drop step adapted for use on passenger cars and the like, with which it is necessary, or desirable, to use a foot stool to afford a stepping member for passengers alighting from and mounting to the steps of the car.

An object of the invention is to provide a moveable step attached to the car which may be moved out of position when desired and readily placed in operative position, so as to eliminate the necessity of using the stepping member which is detached from the car, the present device being operable for movement into operative position by a power operated moving device and adapted for moving to inoperative position in response to the tension of a resilient member placed under tension upon the movement of the power operating device into operative position.

Another object of the invention is the provision of an air cylinder having a piston rod adapted for engaging the movable step for moving it into operative position.

Another object of the invention is the provision in a device of the class described of an air cylinder having a piston rod adapted for projecting through a resilient member and attached, at its free end, to the movable step, the resilient member being for restoring the movable step to inoperative position upon the release of the air from the air cylinder.

Other objects will appear hereinafter.

The invention consists in the combination and arrangement of parts hereinafter described and claimed.

The invention will be best understood from a reference to the accompanying drawings which form a part of this specification and in which,

Fig. 1 is a fragmentary side elevational view of a car embodying the invention,

Fig. 2 is a side elevational view of the attaching means for supporting the movable step,

Fig. 3 is a longitudinal central vertical

sectional view of the invention applied to a step,

Fig. 4 is a rear elevational view of the invention applied to a step.

As shown in the drawings, the invention is used with a passenger car 7, or the like, having steps 8 mounted adjacent a vestibule at the ends thereof. These steps generally terminate a distance above the surface over which the car is propelled, so as to afford sufficient clearance for any obstruction which may be positioned on the right-of-way. The result is that the steps are at too great an elevation to afford easy mounting and dismounting thereon and therefrom, necessitating the use of a footstool or the like to assist passengers in boarding and dismounting from the cars. The present invention is provided to obviate the necessity of using the foot stool by providing a slideable step positioned beneath the lowermost step 9 and so arranged as to be moved into operative and inoperative position at will. The steps 8 are secured at their ends to side members 10 and 11. Mounted on these side members, at opposite sides, are metallic strips 12 having a plurality of elongated slots 13 formed therein longitudinally thereof so as to engage studs or bolts 14 driven into the members 10 and 11. The slideable or auxiliary step 15 is securely mounted to the lower edge of the members 12 in any desired manner. Mounted by suitable brackets 16 and 17, beneath the steps 8, intermediate the ends thereof, is a cylinder 18 adapted for operating by air a supply of which is delivered to the car. Suitable piping communicates to the cylinder 18 and is provided with suitable control valves. This piping and the control valves are not shown inasmuch as any customary method of connecting the cylinder of the air supply of the car will suffice. Slideably mounted in the cylinder 18 is a piston 19 having a piston rod 20 projecting from the cylinder and extending through an opening formed in a bracket 21, which is secured to one of the steps 8. Securely attached to the bracket 21 is one end of a coil spring 22, the opposite end 23 of which is fastened to a bracket 24 mounted on the auxiliary step 15 intermediate its ends. The arrangement is such that the movement of the auxiliary step to operative position will place the spring 22 under tension so that the spring 22 normally

tends to retain the moveable step in inoperative position or in close engagement with the under surface of the lowermost fixed step. The end of the piston rod 20 is swivelly attached to a suitable socket forming portion 25 which is present on the bracket 24. It is to be noted that the piston rod extends through the coil spring 22 and that the projection of the rod through the bracket 21 10 affords a guide for the rod in its reciprocal movements. The projection of the rod through the spring in the manner shown serves to guide the spring in its movements and serves to prevent any bending or buckling of the spring in its movements.

It is thus seen that I have provided a drop step for passenger cars and the like which is power operated and which may be controlled at will by the operator. The 20 most convenient place for mounting the control valves of the air pipes would seem to be in the vestibule. However, this is a matter which may be left to the discretion of the builder. Upon the turning of the air 25 into the cylinder 18, the piston is forced outwardly, so as to move, through operation of the piston rod 20, the auxiliary step 15 into operative position as shown in Fig. 3. When it is desired that the auxiliary step 30 be raised to inoperative position, the air may be turned off and the spring will then cause the auxiliary step to move upwardly into close engagement with the lower step 9, a suitable escape opening being provided 35 in the ordinary manner either in the control valve, the piping or the cylinder.

It is desirable that this cylinder be positioned intermediate the ends of the step as shown, and the positioning of this cylinder 40 may be said to be adjacent the longitudinal axis of the steps, it being understood that a plane bisecting all of the steps would pass through the center of the cylinder.

While I have illustrated and described the 45 preferred form of structure, I do not wish to limit myself to the precise form of structure shown but desire to avail myself of such variations and modifications as come within the scope of the appended claims.

Having thus described my invention, what 50 I claim as new and desire to secure by Letters Patent is:

1. In combination with a vehicle having a plurality of steps and side walls supporting said steps, an auxiliary step adapted for positioning beneath the lower of said steps; 55 slideable supporting members mounted on said auxiliary step and adapted for slideable movement along the side walls associated with said steps; a cylinder mounted adjacent the longitudinal axis of said steps; a piston rod adapted for projecting from said cylinder; means for pivotally mounting the free end of said piston rod to said auxiliary step 60 intermediate the ends of said step; and re-

silient means in parallel relation to said piston rod tending normally to maintain said auxiliary step in inoperative position.

2. In combination with a vehicle having a plurality of steps and side members for supporting the same, an auxiliary step adapted for positioning beneath the lowermost of said steps in slideable relation thereto; means slideably mounted on said side members for supporting said auxiliary step; resilient means for normally maintaining said auxiliary step in inoperative position; a bracket mounted on said step for engaging one end of said resilient means; and power operated means for moving said auxiliary step into operative position, said bracket serving as a guide for said power operated means.

3. In combination with a vehicle having a plurality of steps and side members for supporting the same, an auxiliary step adapted for positioning in slideable relation to said steps beneath the lowermost step; a bracket mounted on said auxiliary step intermediate its ends; a guiding bracket mounted on one of said vehicle steps; a spring attached at one end to said bracket on said auxiliary step and at its opposite end to said guiding bracket; a cylinder mounted on said steps adjacent the longitudinal axis thereof; a piston rod projecting from said cylinder and adapted for passing through an opening formed in said guiding bracket, the free end of said piston rod being pivotally connected to the bracket on said auxiliary step.

4. In combination with a vehicle having a plurality of steps and side members for supporting the same, an auxiliary step adapted for positioning beneath the lowermost of said steps in slideable relation thereto; auxiliary step supporting members mounted on said side members in slideable relation thereto, said auxiliary step supporting members having a plurality of elongated slots formed therein; a bracket formed on said auxiliary steps intermediate its ends; a guide bracket mounted on said steps; a cylinder mounted on said steps adjacent the longitudinal axis thereof; a piston rod projecting from said cylinder and through an opening formed in said guide bracket; and means for pivotally mounting the free end of said piston rod to said bracket on said auxiliary step; and a spring in embracing relation to said piston rod, one end of said spring being attached to the bracket on said auxiliary step and the opposite end being attached to said guiding bracket, said spring being adapted for normally maintaining said auxiliary step in inoperative position relatively to said vehicle steps.

In testimony whereof I have signed the foregoing specification.

SAMUEL POOLE.
